UNITED STATES PATENT OFFICE.

WALTER CORDES, OF GOTHA, GERMANY.

DENTAL ENGINE.

Application filed November 15, 1926, Serial No. 148,583, and in Germany January 2, 1926.

In dental techincs tools executing rotating movements, milling cutters, drills and the like in different shapes are used for making sets of teeth and elements belonging to the 5 same. The tools required are at present inserted the one after the other into a spindle which can be attended by only one man, which not only causes a considerable loss of time but hinders the dentist in carrying out 10 his work very carefully because he must hold the work with one hand and hold the tool in the other hand. Accurate guiding of the tool relatively to the part being worked upon is consequently impossible and the precise 15 carrying out of the work is impeded. In addition, the clamping chuck is worn rapidly by the repeated exchanging of the tools.

The present invention has for one of its 20 principal objects to attain the absolute quietness and security of operation of such a machine which is essential to the work of dentists.

The improved dental engine according to the invention comprises at least three spindles 25 rotated or reciprocated from a common mechanical driving mechanism and adapted to hold a corresponding number of tools, necessary for the treatment of the work.

30 An embodiment of the invention is shown, by way of example, in the accompanying drawings in which:

Fig. 1 is a side elevation of a dental engine embodying the invention.

35 Fig. 2 is a plan view of the gear box without the cover removed.

Fig. 3 is a side elevation of the head stock of one of the rotatable spindles.

40 Fig. 4 is a side elevation, partly in section, of a head stock of one of the reciprocating spindles.

Fig. 5 is an elevation, partly in section, of the portion of the driving shaft which extends through the bottom plate of the gear 45 box.

Figure 6 is a plan view on a larger scale of the gear box with the cover removed and showing the mechanism therein in greater detail.

50 Figure 7 is a sectional elevation of the gear box.

Figure 8 shows on a still larger scale the mechanism for driving the rotary tools, and

55 Figure 9 shows part of the mechanism for driving the reciprocating tools.

The dental engine comprises an upright

a, on which a gear box *b* is mounted, in which gear box any desired number of spindles *c* are arranged and are rotated from a common driving wheel *d*. The spindles *c*, 60 which project through the side walls of the gear box *b*, have each a clamping chuck *e* each of which chucks is designed to hold one of the tools *f* commonly used in dental 65 techniques, i. e. a grinding tool, a cleaning tool, a finishing tool and polishing means. The spindles are packed, at the point at which they extend through the side walls of the gear box *b*, by packing rings *g* of felt or other convenient material in order that the 70 lubricating oil may not escape from the casting past the same.

In order that the engine may be used to 75 actuate reciprocating tools, such as files, saws *h* and the like, which heretofore had to be manually manipulated, a reciprocating movement is communicated to some of the spindles *i* located in the gear box. These spindles *i* are driven also from the common driving wheel *d* and each has a clamping 80 chuck at its outer end for holding a tool and they are oil-tightly packed at the points where they pass through the walls of the box.

All the rotating spindles *c* and also the 85 reciprocating spindles *i* are so constructed that they can be uncoupled, and the rotating spindles *c* can rotate in both directions.

Push buttons *n* for moving the spindles into and out of engagement with the driving 90 wheel *d* extend through the top plate *o* of the gear box *b* so that any of the spindles can be operated at any moment. The improved dental engine can be used by several dentists 95 simultaneously. The top plate *o* of the gear box is so constructed as to support the foot *p* of a lamp having several arms. The gear box is shown as of square cross section but it might be of any other cross section and any number of spindles can be arranged in 100 the gear box and the driving gear may be for any desired ratio of transmission.

The electric motor *k*, supported by the upright *a*, Figure 1, drives by means of a cord the cord pulley *l* of the spindle *l* which 105 is vertically supported in a guide nipple *m* secured to the bottom of gear case *b*. The spindle *l* carries a pinion *w* which meshes with the main driving gear *d* which is centrally mounted in the gear case *b*. The 110 pinion *w* has a bell-shaped portion surrounding the upper end of the guide nipple *m* and

secured to the latter by a nut 31. The nipple *m* extends above the oil level in the gear box, thus making it unnecessary to provide a stuffing box for the spindle *l* where it extends through the bottom of the gear box. The driving wheel *d* meshes with the toothed wheels 2, Figures 6, 7 and 8. The latter are keyed to the spindles 3 of the bevel wheels 4 which are constantly in mesh with the pinions 5 and 6 mounted loosely on the spindles *c*. Either of the pinions 5 and 6 may be coupled to the spindle *c* on which it is mounted by a claw coupling 7 which is longitudinally slideable on and splined at 8 to the spindle *c*. The longitudinal movement of the claw coupling 7 is effected by means of the button *n* carrying at its lower end a fork 9 which engages with an annular groove 10 of the coupling 7. Each button *n* is movable in a slot 11 in the cover *o* of the gear box *b* and in a slot 12^a in the bearing housing 12 and is held in any of its positions by means of a spring 13. Owing to this arrangement, only one of the wheels 5 or 6 is clutched at the same time with a spindle *c*, but both wheels are out of engagement with the claw coupling when the latter is in the central position. The same coupling arrangement is provided for all the spindles *c*. In the drawings are shown nine wheels 2 which are in engagement with the main driving gear *d*. It follows therefore that each spindle *c* can be thrown into gear and out of gear with the driving wheel *d* independently of the other spindles, and each spindle can be caused to rotate in either direction according to the direction in which its button *n* is shifted.

The longitudinal reciprocation of the spindles *i* is also effected by the driving wheel *d*. The wheel *d* carries at its center a sleeve 14 on which a crank pin 15 is eccentrically mounted. This crank pin engages in a slot 16 of a guide part 17 which is connected to the hollow guide sleeves 18 for the spindles *i*. When the wheel *d* is rotated, the crank pin 15 is rotated, and consequently the guide piece 17 and also the guide sleeves 18 are horizontally reciprocated. The latter slide in bearings 19 supported by a bracket 20.

A hook 22 extends into each hollow guide sleeve 18 and has its forward end mounted to rock on a pin 21 carried by a spindle *i*. A spring 24 normally tends to move the hooked end of the hook 22 into a slot 23 in the guide sleeve 18. The lower end of a push pin *n'* normally bears against the hook 22 under the action of a spring 25 so as to normally hold the hook 22 out of engagement with the slot 23 of the sleeve 18. The push pin *n'* has a lateral pin 26. When the said pin is situated inside its casing 27, which happens when the spring controlled pin *n'* is depressed by its spring 25, the hook 22 is disengaged from the slot 23 of the guide

sleeve 18, the spring 24 is compressed, and the corresponding spindle *i* is prevented from reciprocating. If, however, the spring controlled pin *n'* is pulled upwardly to lift its lateral pin 26 above the upper end of the bearing 27, and is then turned to cause its lateral pin 26 to rest upon the upper edge of the bearing 27, the hook 22, under the action of the spring 24, will engage with the slot 23 of the guide sleeve 18, and the latter, when reciprocated by the crank pin 15 through the guide part 17, will reciprocate its associated spindle *i* and the reciprocating tool, such as a filing or sawing tool.

In order to ensure a quiet and secure working, a hand-support *q* is arranged under each tool. Said support also serves to collect the chips from the work. A table plate *r*, fixed on the upright *a* at a certain distance underneath the gear box, contains drawers *s* and supports a vise *t* or the like so that it can serve as working table.

The dental engine described and shown may serve also, if its construction is modified accordingly, for sculptors, goldsmiths, glass cutters, turners, cabinet makers, stucco workers, for wood working, for the toy industry and for similar industries.

The advantages obtained are the following:

All known tools, and any other forms of tools which might be invented and have a certain likeness to known tools, can be mounted in the machine. All tools which at present are used separately, such as grinding tools, cleaning tools, finishing tools, and polishing means, can be mounted in the dental engine and the operation of the machine does not require special skill. By means of the dental engine not only sets of teeth or parts of the same, such as caoutchouc, but also any material as metal alloys, woods, glass, stone, bone, horn, rubber, caoutchouc and india rubber combinations can be treated, ground, cleaned, finished or polished.

I claim:

1. A dental engine, comprising in combination with an upright, a driving engine on said upright, a gear box on said upright above said driving engine, a plurality of spindles in said gear box, means for rotating said spindles from said engine, each of said spindles having means for holding a tool for grinding, cleaning, finishing, or polishing, and a plurality of selective means, one for each spindle for communicating to said spindles a rotating movement, whereby any one of the spindles may be operated singly or all may be operated simultaneously.

2. A dental engine, comprising in combination with an upright, a driving engine on said upright, a gear box on said upright above said driving engine, a plurality of spindles in said gear box, means for rotating said spindles from said engine, each of

said spindles having means for holding a tool for grinding, cleaning, finishing, or polishing, and selective means for communicating to any one or all of said spindles a 5 reciprocating movement.

3. A dental engine, comprising in combination with an upright, a driving engine on said upright, a gear box on said upright above said driving engine, a plurality of 10 spindles in said gear box, each of said spindles having means for holding a tool for grinding, cleaning, finishing, or polishing, means for communicating from said engine to some of said spindles a rotating movement 15 and to certain of said spindles a reciprocating movement, and whereby one or all may be operated simultaneously.

4. A dental engine, comprising in combination with an upright, a driving engine on 20 said upright, a gear box on said upright above said driving engine, a plurality of spindles in said gear box, means on said spindles for holding a tool for grinding, cleaning, finishing, or polishing, a common 25 driving disk actuated by said engine for communicating to said spindles a rotating movement, and selective means for causing the disk to drive one spindle at a time or all spindles simultaneously.

30 5. A dental engine, comprising in combination with an upright, a driving engine on said upright, a gear box on said upright above said driving engine, a plurality of spindles in said gear box, each of said 35 spindles having means for holding a tool for grinding, cleaning, finishing, or polishing, and a common driving disk actuated by said engine for communicating to said spindles a rotating movement, and push but- 40 tons in the top plate of said gear box for engaging or disengaging said spindles with said driving disk and for reversing the direction of rotation of said rotatable spindles.

45 6. A dental engine, comprising in combination with an upright, a driving engine on said upright, a gear box on said upright

above said driving engine and filled with lubricating oil up to a certain height, a plurality of spindles located in said gear box and projecting through the walls of said 50 gear box, a clamping chuck on each spindle and designed to hold a tool, means for communicating from said engine to some of said spindles a rotating movement and to some of said spindles a reciprocating movement, and 55 selective means whereby one spindle may be operated at a time or all spindles may be operated in unison.

7. A dental engine, comprising in combination with an upright, a gear box on said 60 upright above said driving engine and capable of being filled with lubricating oil up to a certain height, a plurality of spindles located in said gear box and projecting through the walls of said gear box, a clamping 65 chuck on each spindle and designed to hold a tool, a guide sleeve carried by the bottom plate of said gear box open at its lower end and projecting at its upper end above the oil level in said gear box, a vertical 70 driving shaft projecting into and through said sleeve, a pinion having a high central portion keyed to the top end of said driving spindle and enclosing the upper portion of said sleeve, means for rotating said driving 75 shaft and means for transmitting the rotat-

ing movement of said pinion to said spindles. 8. A dental engine, comprising in combination with an upright, a driving engine on 80 said upright, a gear box on said upright above said driving engine, a plurality of spindles in said gear box, each of said spindles having means for holding a tool for grinding, cleaning, finishing, or polishing, means for communicating rotary move- 85 ment to said spindles from said engine, a top plate on said gear box, a lamp foot on said top plate, and a lamp having several arms mounted in said foot.

In testimony whereof I have hereunto set 90 my hand.

WALTER CORDES.
